UNITED STATES PATENT OFFICE.

SAMUEL KAYE, OF COLUMBUS, MISSISSIPPI.

CROWN-FEEDER FOR BOTTLE-CAPPING MACHINES.

1,304,323.

Specification of Letters Patent. Patented May 20, 1919.

Application filed February 7, 1916. Serial No. 76,791.

To all whom it may concern:

Be it known that I, SAMUEL KAYE, a citizen of the United States, residing at Columbus, in the county of Lowndes and State of 5 Mississippi, have invented certain new and useful Improvements in Crown-Feeders for Bottle-Capping Machines, of which the following is a specification.

My invention relates to an improvement 10 in crown-feeders for bottle-capping machines.

The primary object is to automatically supply bottle crowns in proper position and with precision to the capping-finger, preparatory to its insertion by the finger from beneath up into the filling-head, as fully set forth in an accompanying application.

My present invention consists in a chute which the crowns fit loosely, and down 20 through which they are fed by gravity, a gate at the bottom of the chute which is raised and lowered at timed intervals to control the escape of the crowns from the chute, in connection with a stationary guide, and 25 a reciprocating carrier, which is guided in its movements by the stationary guide, and having a slot throughout the major portion of its length. The edges of this slot are inclined so that the lowermost crown in the 30 chute is permitted to rest undisturbed with one edge upon the stationary guide, supporting the crowns above while the gate is closed, and the carrier is moving throughout a portion of its backward travel, while the 35 crown which has just left the chute is being held against backward movement by the lowermost crown, while the carrier is being withdrawn from beneath it, and another crown at the extreme forward end of the 40 carrier is being stripped therefrom and left in position to be removed by the oncoming capping-finger. The return forward movement of the carrier conveys forward a crown left on its forward end to a point where it is 45 deposited in position to be received by the next oncoming capping-finger. The gate is opened, just before the carrier has reached the end of its forward stroke, to release another crown from the chute upon the upper 50 flat surface of the carrier, which is in position to receive it just back of the slot. Here it is held against returning with the carrier on its backward movement by the lowermost crown in the chute, until the carrier starts 55 upon its return forward stroke, when it is in position to be pushed forward and de-

posited and left by the carrier. In the meantime, another crown has been released and deposited upon the upper flat surface of the carrier, and a third crown is resting vertically behind. 60

In the accompanying drawings:—

Figure 1 is a vertical section in which the gate has nearly completed its upward movement, and the lowermost crown has started 65 to leave the chute with its edge resting upon the table below, and another crown part way to its final position;

Fig. 2 is a similar section, but showing the gate dropped to its normal position, and 70 the crown (which in Fig. 1 had started to leave the chute) now resting upon the upper flat surface of the carrier, and the preceding crown at the forward end just ready to be left suspended upon the spring-fingers preparatory to being removed by a capping-finger; 75

Fig. 3 is a similar sectional view showing the carrier at the extreme limit of its backward stroke, with one crown resting upon 80 the spring-fingers, another crown in position to be pushed forward with the forward stroke of the carrier, and a third (the lowermost crown in the chute) resting with its lower edge just back of the crown at the forward end of the carrier; 85

Fig. 4 is a plan view;

Fig. 5 is a view in front elevation looking to the left, showing the gate lifted;

Fig. 6 is a plan view of the carrier; 90

Fig. 7 is a detail perspective view of the gravity guard;

Fig. 8 is a perspective view of the carrier and crown-chute; and

Figs. 9, 10, 11 and 12 are details in different positions showing the various positions of the crown during the progressive stages of its passage from the spring-fingers. 95

A, represents a stationary guide secured to the upper end of a support 1, which is 100 erected upon a suitable base 2.

A carrier 3 is slidably connected with the stationary guide A, and is bolted to the upper end of a column 4, as shown in Figs. 1, 2, 3, 4 and 6. This column is preferably 105 erected upon the upper end of a slide-bar 5, which moves through a guide-slot 6 in the base 2, see Fig. 5. The carrier 3 has a slot 7 extending centrally throughout the major portion of its length, the edges 8, 8, of which 110 are inclined, and the forward ends 9, 9, of which edges are fashioned substantially into

the shape of the edge of a crown, whereby to fit the crown when received on the flat forward end 10 of the carrier, as shown in Fig. 6.

5 The purpose of the slot 7 and the inclining edges 8, 8, is to allow clearance for the lowermost crown in the chute when its edge is resting upon the stationary guide below, while the carrier is moving back, previous to its escape from the chute, as shown in Fig. 5.

10 A U-shaped frame 13 is secured at the upper end of the column 4, and disposed parallel with the carrier with which it travels, and at the forward ends thereof the inclined guide-tracks 14 are formed, as shown.

15 A shallow crown-chute 15 is erected vertically above the stationary guide A, its greatest width extending transversely thereof, and its depth being sufficient to nicely accommodate the crowns C, which descend therethrough, one thus being held above another, as illustrated in several of the views.

20 A vertically slideable gate 16 controls the lower end of the chute, where it is held slidably in place by guides 17. This gate is raised and lowered by a swinging-support 18, which is pivotally connected with the edges of the gate by screws or pins 19, 30 19. This swinging support extends around the sides and back of the chute, so that it has a limited forward swinging movement, whereas it may be swung backward out of the way.

25 At the lower end, it has the anti-friction rollers 21, and these rollers are in the path of the inclined guide-tracks 14, 14, on the forward end of the U-shaped frame 13, so that with the forward movement of the carrier and U-shaped frame the rollers 21, 21, ride up upon the guide-track, and the gate is raised slowly, after which it is suddenly dropped by the rollers passing over the rear end of the guide-tracks 14, and 40 45 dropping to the horizontal surface of the U-shaped frame below. With the movement in the opposite direction, the backward movement of the carrier and U-shaped frame, the swinging-support 18 is brushed aside, swinging from the pivotal connection with the gate without affecting the position of the gate. Adjustable set-screws 20 regulate the fall of the gate.

50 A weighted gravity guard 23, shown in perspective in Fig. 7, is located in position to prevent the crowns from lifting or crowding out of place after leaving the chute (see the left hand crown in Figs. 2 and 3).

55 60 A spring-actuated catch 24 strips the cap C' at the forward end of the carrier from the end 10 thereof when the carrier moves back, or in the direction indicated by the arrow in Fig. 3, and leaves it resting between the spring-fingers 25 and the plate

22 above, preparatory to being removed therefrom by the approaching cap-finger F. The lowermost crown in the chute holds the crown having left the chute from backward movement with the carrier, and 70 finally insures its dropping to the lower flat surface 10 at the forward end of the carrier immediately in front of the ends 9, 9, when the carrier shall have moved to its extreme backward position, as is illustrated first 75 by Fig. 2, and then by Fig. 3.

In operation, let us start with the position shown in Fig. 1. The carrier is still moving forward, or to the right. The ends 9, 9, of the carrier are pushing the cap C' 80 beneath the catch 24, and are about to leave it on the spring-fingers 25, and between the latter and the plate 22. The vertically sliding gate 16 has been opened and a crown C has left the chute, it having been laid down 85 upon the upper flat surface of the carrier. In Fig. 2, the carrier has moved still farther forward or in the direction indicated by the arrow. It has carried the right hand cap C' to a position between the spring-fingers 90 25 and the plate 22, but has not yet deposited it. The cap is still resting upon the end 10 of the carrier, and the carrier has carried the cap C (which in Fig. 1 had just left the chute) a little forward on the upper flat surface of the carrier beneath the guard 23, as shown in Fig. 2.

The carrier has now reached its extreme forward movement, and is ready to return.

Fig. 3 shows it in its extreme backward movement, the tracks 14 have pushed the rollers 21 aside out of their way, the catch 24 has stripped the right hand cap C' from the end 10 of the carrier, leaving it between the spring-fingers and plate 22, and the cap 100 at the lower end of the chute has prevented the left hand cap C from moving back with the carrier and caused it to drop in front of the ends 9, 9, of the carrier, (all of which is shown in Fig. 3) just as the carrier shall 105 110 have reached its extreme backward movement. Now on the forward movement of the carrier, its several operations are repeated, cap C taking the place of cap C', which latter has just been removed by the 115 capping-finger F, and the gate opening to permit the escape of the lowermost cap of the chute.

At the outer end of the plate 22, and over the ends of the spring-fingers 25, a 120 weighted flexible tongue T depends in the path of the crown, as shown in Figs. 1, 2, 3, 4, and 9 to 12 inclusive, the function of the tongue being to furnish a slight resistance to the movement of 125 the crown. This resistance tends to effectually seat the crown properly on the capping finger sleeve as the latter moves it from between the plate 22 and the spring-fingers 25. By referring to Figs. 9 to 12, the vari- 130

ous positions will be shown. In Fig. 9, the cap has not reached the tongue, whereas in Fig. 10 it is in engagement therewith, and commencing to be resisted by it; in Fig. 11 it has been nearly removed from the spring-fingers; and in Fig. 12 it has been entirely removed, but the weighted end of the tongue is still resting upon the crown to insure its being properly placed over the top of the 10 capping-finger.

I claim:

1. A crown-feeder for bottle-capping machines comprising a stationary guide having a comparatively narrow interior which 15 receives the caps and presents them edge-wise, a vertically-disposed crown-chute, a gate therefor, which opens and closes a portion only of one side of the chute, and a reciprocating carrier at the bottom of the 20 chute which receives and places said crowns, and said reciprocating carrier having means which positively effects the opening and closing of the gate automatically.

2. In a crown-feeder for bottle-capping 25 machines, the combination of a stationary guide, a crown-chute vertically erected thereon, a carrier fitted to and reciprocating in the guides, a gate slidably connected with the chute, a swinging support pivotally 30 connected therewith and extending back of the chute to limit its forward swing, and a frame connected with the carrier and provided with inclined tracks in the path of the lower end of the swinging support for 35 slowly raising and allowing it to suddenly drop by gravity at predetermined intervals.

3. In a crown-feeder for bottle capping 40 machines, the combination of a stationary guide, a reciprocating carrier having a slot extending throughout the major portion of its length with flat surfaces at the ends thereof, and provided with means fashioned to fit and engage the edge of a crown, spring-fingers slightly beneath one end of the 45 stationary guide, adapted to receive the crown thereon when carried there by the carrier, a catch in position to cause the crown to be deposited upon the spring-fingers when the carrier is withdrawn from beneath the crown, a vertically-disposed chute having a vertically slideable gate, a 50 swinging support pivotally connected with the gate and its sides connected together back of the chute, thereby acting to limit the forward swing of the support, a frame 55 connected with the carrier and carrying tracks in position to move beneath said swinging support, whereby to cause a gradual lifting of the gate, and a sudden drop of the latter when the tracks pass from beneath the support, the latter being pushed aside by the tracks on the return movement of the carrier.

4. In a crown-feeder for bottle capping 60 machines, the combination of a stationary

guide, a reciprocating carrier having a slot extending throughout the major portion of its length with flat surfaces at the ends thereof, and provided with means fashioned to fit and engage the edge of a crown, spring-fingers slightly beneath one end of the stationary guide, adapted to receive the crown thereon when carried there by the carrier, a catch in position to cause the crown to be deposited upon the spring-fingers when the 70 carrier is withdrawn from beneath the crown, a vertically-disposed chute having a vertically slideable gate, a swinging support, pivotally connected with the gate and its sides connected together back of the chute, 80 thereby acting to limit the forward swing of the support, a frame connected with the carrier and carrying tracks in position to move beneath said swinging support, whereby to cause a gradual lifting of the gate, and a sudden drop of the latter when the tracks pass from beneath the support, the latter being pushed aside by the tracks on the return movement of the carrier, a guard beneath 85 which the crowns move on leaving the chute, a catch, said catch and the lower end of the chute acting to prevent the two caps located at different points on the carrier from returning with the latter when it makes its backward stroke. 90

5. In a feeder for bottle-capping machines, the combination of a stationary guide, a reciprocating carrier movable therein, a frame connected with the carrier and having guide-tracks thereon, a chute erected above the stationary guide to receive and feed crowns, the carrier having an elongated slot throughout the major portion of its length with inclined sides, and having means at or near the forward end of the slot fashioned to fit the edge of a crown, a sliding gate, and a swinging support pivotally connected with the gate and limited by the chute in its forward movement, but unlimited in its backward movement, and its lower end depending in the path of the guide-tracks on the frame below, whereby to ride up and drop from the tracks when the carrier is moved in one direction, and be swung aside by the tracks when the carrier 105 is moved in the opposite direction. 110

6. In a feeder for bottle capping machines, the combination of a stationary guide, a reciprocating carrier movable therein, a frame connected with the carrier and having guide-tracks thereon, a chute erected above the stationary guide to receive and feed crowns, the carrier having an elongated slot throughout the major portion of its length with inclined sides, and having means at or near the forward end of the slot fashioned to fit the edge of a crown, a sliding gate, a swinging support pivotally connected with the gate and limited by the chute in its forward movement, but unlimited in its 120 125 forward movement, and having means at or near the forward end of the slot fashioned to fit the edge of a crown, a sliding gate, a swinging support pivotally connected with the gate and limited by the chute in its forward movement, but unlimited in its 130

- backward movement, its lower end depending in the path of the guide-tracks on the frame below, whereby to ride up and drop from the tracks when the carrier is moved 5 in one direction, and be swung aside by the tracks when the carrier is moved in the opposite direction, and means located respectively above and below the path of the carrier, one of which is to remove a crown 10 therefrom, and the other to support and hold the crown, and a capping-finger for removing the crown from said support.
7. In a crown feeder for bottle capping machines, the combination of spring-fingers, 15 a clamp, and means for depositing the crown at a point between the spring finger and clamp, a weighted flexible device resting in

the path of the escaping crown, and means for removing the crown from the spring-fingers against the resistance of the flexible 20 device.

8. In a crown-feeder for bottle capping machines, the combination of spring-fingers, a clamp, and means for depositing the crown at a point between the spring-finger and 25 clamp, a weighted flexible device resting over the outer ends of the spring-fingers and in the path of the escaping crown, and means for removing the crown from the spring-fingers against the resistance of the flexible 30 device.

In testimony whereof I affix my signature.

SAMUEL KAYE.
